UNITED STATES PATENT OFFICE

157,130

FLOOR MAT

Roger Harry David, St. Paul, Minn.

Application December 27, 1948, Serial No. 150,392

Term of patent 14 years

(Cl. D9—6)

To all whom it may concern:

Be it known, that I, Roger Harry David, a citizen of the United States, residing at St. Paul, county of Ramsey, and State of Minnesota, have invented a new, original, and ornamental Design for a Floor Mat, of which the following is a specification, reference being had to the accompanying drawing, forming part thereof:

I claim:

The ornamental design for a floor mat, as shown.

ROGER HARRY DAVID.
